John Edward Delbridge
INVENTOR

By Otto Munk, his Attorney.

Patented Oct. 12, 1926.

1,602,754

UNITED STATES PATENT OFFICE.

JOHN EDWARD DELBRIDGE, OF NORTHCOTE, NEAR MELBOURNE, VICTORIA,
AUSTRALIA.

HINGE.

Application filed December 12, 1922, Serial No. 606,386, and in Australia July 4, 1922.

This invention relates to improvements in hinges for doors, windows and the like, and it is particularly applicable to hinges for the doors of automobiles and other vehicles 5 wherein a desideratum is the provision of a hinge having its elements so constructed and co-acting that they can be conveniently secured to a door and a door frame in such manner that the point of hinge connection is 10 concealed from view.

An object of the invention is to provide a hinge having its two members hingedly and detachably connected whereby a door or other swinging object can be conveniently 15 removed bodily, without altering or adjusting the hinge elements affixed to the door and to the door frame, and without necessitating removal of screws or like fastenings employed to fasten the hinge leaves in operative position.

A further object of the invention is to provide a hinge of specially simple construction comprising a stationary element adapted for attachment to a stationary frame, and a 25 movable element for affixture to the door or like swinging object, the two elements being so constructed that they can be readily connected for hinging movement, and conveniently detached without requiring the use of 30 screws or additional fittings other than the two hinge elements.

A hinge according to the invention can be designed for adaptation to doors, self-closing wire screens, windows, articles of 35 furniture and other swinging and movable objects, and it is characterized by consisting of a stationary element adapted to receive the hinge pin of a movable element, engagement being effected by an initial 40 slidable movement of the movable element in guides formed in the stationary element until the two parts are brought to and automatically locked in the hinging position.

Representative constructions of hinges 45 according to my invention are illustrated in the accompanying drawings wherein:

Figure 1 is a view in plan of a hinge applied to a door of an automobile or other vehicle, the door being in its closed position and the hinge connection concealed from external view.

Figure 2 is a plan view similar to Figure 1, but showing the door in open position.

Figure 3 is a plan illustrating the door

in position for removal by disengagement of 55 the hinge elements.

Figure 4 is a front elevation of the stationary element of the hinge.

Figure 5 is a side elevation of Figure 4.

Figure 6 is a plan of Figure 4.

Figure 7 is a sectional plan on line a—a 60 Figure 4.

Figure 8 is a vertical section on line b—b of Figure 4.

Figure 9 illustrates in side elevation the 65 movable hinge element.

Figure 10 is an end elevation of Figure 9.

Figure 11 is a vertical section on line c—c of Figure 1 showing the position of the movable hinge element when the door is 70 closed.

Figure 12 is a vertical section on line d—d of Figure 3, showing the position of the movable hinge element when the door has been raised so as to free the same from the 75 stationary hinge element.

Figure 13 is a fragmentary sectional view on line e—e of Figure 11.

Figure 14 is an underside plan of the lower portion of the hinge pin on the movable element.

Referring now to Figures 1 to 14 of the drawings, which are illustrative of a hinge of the "concealed" type (such as is employed for the doors of automobiles and other vehicles), the numeral 4 designates the stationary element or leaf of the hinge, which is in the form of a metal bracket having a flat base plate 5 having holes 6 to accommodate screws, firmly securing said hinge element to 90 the door frame A about a recess A¹ formed therein.

Constructed integrally with the base plate 5 are two slotted lugs 7 which project at right angles from its rear surface and extend into the framing recess A¹. These lugs are disposed one above the other at an approved distance apart to accommodate the movable hinge element 8 as illustrated in the drawings. For this purpose an opening 9 100 is formed in said base plate between the slotted lugs in order that the hinge pin portion of said movable element can be caused to first slidably engage with said lugs and then be rotatably supported thereby.

The slot 10 in each lug 7 is approximately of keyhole configuration, but having its narrow guide portion extending through the

lug and through the base plate 5, thereby providing an open entrance end 11. The entrance ends of the slots are adapted to slidably receive the upper and lower end portions of a hinge pin 13 formed on or secured to the movable hinge element 8. The inner enlarged portions 14 of said slots are of circular configuration and function as bearings for said hinge pin when the door, to which the element 8 is affixed, is in its swinging position, while a rectangular shaped slot 15 is provided in said base plate 5 above the upper lug 7 to permit free passage of the upper portion of said hinge pin when there is being effected a disengagement of the hinge elements, such as, for example, when a door is being bodily removed.

The movable hinge element 8 is constructed with a curved arm 16 having at one end 20 a flat plate 17 formed with holes 18 to receive attachment screws, whereby it is fixedly secured to a door E. A boss 19 is provided at the opposite end of said curved arm, and it is of such dimensions as to be rotatably supported between the slotted lugs 7 of the stationary hinge element 4, while the hinge pin 13 projects from the opposite ends of said boss and is adapted to be revolvably supported in said slotted lugs.

The hinge pin is preferably constructed integrally with the boss 19, and it is adapted so that it can be placed in slidable engagement with the narrowed portions of the key-hole slots 10 in the lugs 7 of the stationary hinge element, or be revolvably supported in the inner circular shaped portions 14 of said slots. For this purpose, each end portion of the hinge pin has a circular-section pintle member, and these are designed so as to be revolvable within the enlarged portions of said slots when the door is being opened or closed, while beneath said pintles are rectangular-shaped members 20 and 21 which are so positioned relatively to the key-hole slots 10 of the co-acting hinge elements that the door B, for removal purposes, must be brought into the position seen in Figure 3, wherein said hinge pin portions 20 and 21 lie directly beneath and in alignment with the narrowed portions of said slots, thus enabling the door with its attached hinge element 8 to be raised vertically whereby said portion 20 and 21 are brought into slidable engagement with the narrowed elongated members of the slots and the pintles are raised clear of the circular shaped members 14 of said slots, as illustrated in Figure 12.

When the door and its attached hinge element have been raised as described, a sliding movement in an outward direction is imparted to the door, as indicated by the dotted lines, to disengage the hinge pin 13 from the slotted lugs 7, the openings 9 and 15 in

the base plate 5 facilitating this action whereby the door is conveniently removed 65 without manipulating any screws or like fastening integers.

To hingedly replace the door, the rectangular-shaped members 20 and 21 of the hinge pin 13 are initially inserted in the entrance ends 11 of the key-hole slots 10 formed in the lugs 7 of the stationary hinge element 4. A forward movement is then imparted to the door, causing said rectangular hinge pin members to be guided slidably inwards, when the weight of the door will result in the pintles of said hinge pin automatically and revolvably engaging the enlarged end portions 14 of said slots, the boss 19 being seated between the lugs 7 and upon the lower thereof.

In order to prevent accidental movement of the movable hinge member 8 in a vertical plane, such as might be caused by slamming of the door, or vibration, or other causes, the upper rectangular member 20 of the hinge pin 13 extends a required distance beyond the upper pintle, and this extension (indicated by 22) bears against the underside of the upper slotted lug 7 when the door is in its operative position, thereby functioning as an effective locking stop—see Figure 11.

The curved formation of the arm 16 and the general arrangement of the other integers of the movable hinge element 8 in relation to the stationary hinge leaf or element 4 permit the hinge connection of the door of an automobile or other vehicle with its body or door frame to be concealed from external view, as will be clearly understood by making reference to Figure 1. The wall 9^a around the opening 9 formed in the base plate 5 of the stationary hinge element functions as a stop by engaging with the curved arm 16 of the movable hinge element, thereby preventing the door B from being swung open beyond a reasonable limit.

What I do claim is:—

A hinge comprising a stationary element consisting of a base plate, a lug on said base plate, an open mouthed slot of key-hole configuration formed in said base plate above said lug, and a swinging hinge element consisting of an attachment plate, a curved arm carried by the attachment plate, a boss on said arm, a pintle on said boss to revolvably engage the enlarged portion of said slot, a flattened member of reduced diameter beneath said pintle adapted to register with and slidably engage the narrowed portion of said slot, and a locking stop to prevent accidental detachment of said movable element.

In testimony whereof I affix my signature.
JOHN EDWARD DELBRIDGE.
